UNITED STATES PATENT OFFICE.

JAMES G. MACLAREN, OF SYRACUSE, NEW YORK, ASSIGNOR TO THE LAMSON COMPANY, OF SYRACUSE, NEW YORK, A CORPORATION OF MASSACHUSETTS.

POWER-CONTROL APPARATUS FOR PNEUMATIC-DISPATCH SYSTEMS.

Application filed May 12, 1926. Serial No. 108,532.

This invention pertains to pneumatic dispatch systems of the so-called "minimum flow" vacuum type and relates more particularly to automatic power controlling apparatus for use in such a system.

Power control apparatus of this general character is disclosed in the patent to Libby No. 968,576, dated August 30, 1910. The patented apparatus provides automatic pressure actuated means for initiating a carrier impelling air flow through the transmission tube whenever a carrier is entered therein as well as means for cutting off such flow after the lapse of a predetermined period of time. While I regard the patented device as generally correct in principle and highly effective in practice, I believe it preferable to have the cessation of carrier impelling air flow depend directly upon the discharge of the carrier from the delivery end of the tube rather than upon the operation of a timing device, and the principal object of this invention is to provide an improved power control apparatus comprising means actuatable automatically upon insertion of a carrier within the dispatch terminal to initiate flow of the air propelling current and also operating automatically when the last carrier emerges from the delivery terminal to cut off the air current abruptly.

In the accompanying drawings, I have illustrated one preferred embodiment of the invention by way of example, and in the drawings,

Fig. 1 is a fragmentary elevation, partly in section, illustrating a portion of the central station desk of a pneumatic dispatch system having the improved power control apparatus applied thereto;

Fig. 2 is a vertical section to larger scale through the casing of the improved power control apparatus showing the several parts in the position which they occupy when the transmission tube is idle;

Fig. 3 is a view similar to Fig. 2, but showing the parts in the position which they occupy at the instant that carrier impelling air flow is initiated;

Fig. 4 is a similar view, showing the parts

in the position which they occupy during the latter portion of the flight of the carrier through the tube;

Fig. 5 is a similar view, showing the parts in the position which they occupy at the instant after discharge of the last carrier from the tube;

Fig. 6 is a fragmentary section on the line 6—6 of Fig. 7, showing the latch controlling vane within the casing; and

Fig. 7 is a fragmentary front elevation of the casing of the apparatus showing the means for controlling the vane.

Referring to the drawings, the numeral 1 indicates a fragmentary portion of the central station desk of a pneumatic dispatch system, comprising transmission tubes, such, for example, as the tube 2, which lead from the central station desk to remote sending or clerks' stations. Each tube is furnished with a delivery terminal 3, and is provided with a continuation 4 leading to the casing 8 of an individual power control device, indicated generally by the numeral 5. This power control device is connected by means of a suction tube 7 to a vacuum drum or header 9, in which a low pressure is continually maintained by means of a suitable pump, exhauster, or equivalent apparatus, not shown.

An open-ended dispatch terminal 6 is provided at the central station for each of the transmission stations 2, such dispatch terminal forming the entrance to that run of the tube which leads to the corresponding remote sending station. The above arrangement in general is old and well known in this art, and further details thereof are, therefore, unnecessary, the present invention being directed to improvements in the power control apparatus per se.

Referring more particularly to Figs. 2 to 7, the improved control apparatus as herein disclosed comprises a hollow casing 8 divided by a partition or septum 10 into an inlet chamber 11 communicating with the tube 4 and an outlet chamber 12 communicating with the tube 7.

As I prefer to employ a balanced valve

for controlling the air flow through the transmission tube, I make the partition or septum 10 of substantially U-shape having the parallel spaced walls 13 and 14. These walls are furnished with coaxial valve apertures 15 and 16, respectively, with which co-operate the heads 17 and 18 of a balanced valve having a stem 19. The valve stem 19 is guided in an opening in a boss 20 on the upper wall 21 of the casing 8 and also in a guide opening in the lower end of a gland 22 having screw-threaded engagement with an opening in a removable cover plate 23. This cover plate 23 normally closes an opening 24 which gives access to the interior of the casing 8 and through which the valve heads may be introduced.

A coiled spring 25 is seated within the gland 22 and bears against the lower head 18 of the valve. This spring tends to close the valve and hold the heads 17 and 18 in closed position so as substantially to cut off the flow of air through the transmission tube. The spring 25 may be adjusted by turning the gland 22.

Preferably the gland is enclosed in a removable cap 26 having an adjustable stop member 27 at its lower end adapted to engage the valve stem 19 and thus to limit the opening of the valve.

Preferably the valve stem is provided at its upper part with a stop finger 28 engageable with the adjustable stop 29 suitably supported upon the casing and which is adapted to limit the closing movement of the valve. In the preferred mode of use of the apparatus the adjustable member 29 is so set as to prevent the valve heads 17 and 18 from closing entirely, thus providing for the minimum flow of air which forms a feature of apparatus of this type. While it is preferred to provide the minimum flow in this way, it is contemplated that it may be obtained in any other usual manner, for example, by providing an opening in septum 10 or by the use of a tube or pipe exterior to the article and leading from the chamber 11 to the chamber 12.

The upper wall 21 of the casing proper is provided with an upstanding annular flange 30 which cooperates with a hollow cover member 31 to form a diaphragm housing. Within this housing is arranged a flexible diaphragm 32 which may hereinafter be referred to under the broad term "pneumatic", since this diaphragm is regarded as exemplifying any air operated device, for example, a piston, bellows, or the like, which responds to variations in pressure, and thereby moves a part to be actuated.

This diaphragm 32 divides its housing into an upper chamber 33 and a lower chamber 34. The diaphragm 32 is provided at its center with an elongate sleeve 35 telescoping over the valve stem 19. The lower

end of this stem is provided with an enlargement 36 adapted to engage a collar or abutment 37 fixed to the valve stem 19 at a point within the chamber 34. The tubular sleeve or stem 35 slides in an opening in a boss 38 in the cover member 31 of the diaphragm housing. A coiled spring 39, preferably of conical shape, so that it may collapse into the smallest possible space, is arranged within the chamber 34 and bears at one end against the diaphragm and at its other end against the upper surface of the wall 21. Spring 39 thus tends to raise the diaphragm into its uppermost position as shown in Figs. 2, 4 and 5.

The chamber 34 communicates freely with the inlet chamber 11 of the main casing by means of a constantly open port 40. Chamber 34 communicates with the chamber 33 by means of a passage 41 controlled by a needle valve 42, the passage 41 normally being of much less capacity than the port 40.

A port 43, preferably of relatively large capacity, as compared with the passage 41, is provided in the cover 31, such port normally being open and permitting atmospheric pressure to act upon the upper side of the diaphragm 32.

An auxiliary valve 44 is adapted at times to close the port 40. This valve 44 is carried by a lever 45 pivotally supported upon a pin 46 carried in spaced brackets mounted upon the cover member 31. A pin 47 projects from the lever 45 near its free end, and one end of a coiled spring 48 is attached to this pin 47. The other end of this spring is secured in an eye 49 at the lower end of a bracket 50 secured at the upper end of the valve stem. The position of the bracket 50 with its eye 49 is such that as the valve stem 19 moves from its uppermost position, as shown in Fig. 2, to its lowermost position, as shown in Fig. 3, the eye 49 passes from a point above the plane defined by the pin 47 and the pivot 46 to a point below such plane, and so that in the first position the spring 48 tends to hold the valve 44 open, while in the second position the spring tends to hold the valve closed.

The valve stem 19 is furnished with a recess 51, preferably in the form of a groove encircling the stem, such recess normally being disposed within the boss 20. This boss is furnished with a radial opening for the reception and guidance for one end of a sliding latch rod 52, whose opposite end is guided in an abutment 53. This latch rod is provided with a collar 54 forming an abutment for one end of a spring 55 encircling the rod. The other end of this spring bears against the abutment 53 so that the spring tends to move the latch rod to the left as viewed in Figs. 2 to 5. The latch rod 52 is provided at its right-hand extremity with a disk or button 56.

A shaft 57 (Figs. 2, 6 and 7) extends transversely across the inlet end of the casing 8, the opposite ends of the shaft being journaled in suitable bearings in the casing, 5 and this shaft carries a vane or baffle plate 58 disposed within the entrance of the casing and in the path of the air current flowing through the transmission tube.

The shaft 56 extends beyond one side of 10 the casing and at this side the casing is furnished with a bracket 59 carrying opposed adjustable stop members 60, 61. An arm 62 secured to the upwardly extending end of the shaft 57 plays between the stops 15 60 and 61, which thus determine or limit the swinging movement of the vane 58. The arm 62 is furnished with a screw-threaded tail portion 63 for the reception of a nut 64 having one or more apertures for the reception 20 of one end of a spring 65 whose opposite end is secured to a fixed pin 66. This spring tends to hold the arm 62 against the stop 60 so that the vane 58 is normally disposed, as 25 shown in Figs. 2, 3 and 4, with its plane oblique to the air current and with its free edge directed oppositely to the stream of air.

The vane 58 is provided with a pair of upwardly extending fingers 67 spaced to receive the latch rod 52 between them and 30 adapted to engage the button 56 and to move the latch rod to the right when the vane is swung downwardly into the position shown in Fig. 5.

The operation of the device is substantially 35 as follows, it being assumed that the parts are normally positioned as shown in Fig. 2. In this position the port 43 is open, the valve heads 17 and 18 are cutting off carrier impelling air flow through the tube, although a minimum flow is permitted, and 40 the vane 58 is disposed as shown in this figure, while the latch rod 52 is inoperative, the recess 51 being disposed above the end of the latch.

45 When a carrier is introduced into the transmission tube, either at the open terminal 6 or at the remote sending station, the minimum flow of air through the tube is cut off or substantially reduced so that the 50 pressure in the chamber 34 falls below normal. This decrease is sufficient to permit atmospheric pressure, acting upon the upper side of the diaphragm, to depress the latter in opposition to the action of the spring 39. 55 As the diaphragm 32 moves downwardly, the member 36 forces the abutment collar 37 of the valve stem downwardly, compressing the spring 25 and moving the stem 19 and the valve heads 17 and 18 to the full 60 open position shown in Fig. 3. As the stem reaches the lower limit of its movement the recess 51 is brought opposite to the latch 52 and the latter snaps into the recess, thus 65 positively locking the valve in open position. During the downward movement of

the valve stem the eye 49 of the bracket 50 passes below the pivot 46 of the lever 45 and the valve 44 is snapped into closed position, thus cutting off atmospheric pressure from the chamber 33.

70 The carrier now makes its flight through the tube, since a full carrier impelling air flow is permitted through the open valve ports 15 and 16. As soon as the valve ports 15 and 16 are opened, a greatly reduced pressure is produced in the chamber 11 and this is immediately transmitted to the chamber 34 through port 40. The air is now gradually sucked out of the closed chamber 33 through the by-pass 41 until the pressure 80 is balanced upon opposite sides of the diaphragm, whereupon the spring 39 restores the diaphragm to its uppermost position, as shown in Fig. 4. Since the diaphragm is not positively connected to the valve stem, 85 this upward movement may take place without reference to the position of the valve which remains open and locked during the remainder of the flight of the carrier.

When the carrier emerges from the tube 90 a sudden rush or gust of air through the tube is produced, and this rush of air, striking the vane 58, swings the latter downwardly in opposition to the spring 55, it being understood that the latter is so tensioned that it holds the vane in the position shown in Fig. 2 in opposition to the normal carrier impelling flow of air which takes place during the flight of the carrier. As the 95 vane 58 swings down in response to the sudden rush of air at the exit of the carrier, the fingers 67 engage the button 56 and retract the latch rod 52 from the recess 51. The spring 25 immediately becomes active to snap the controlling valve into its closed 100 position, and as the valve stem nears its uppermost position the spring 48 again opens the auxiliary valve 44, thus permitting atmospheric pressure to act upon the upper side of the diaphragm. The parts are thus 105 restored to their original position ready for a repetition of the cycle.

In the arrangement thus described the closure of the main valve is dependent solely upon the delivery of the last carrier from 115 the tube, and there is no possibility of partial closure of the main valve prior to such delivery, since the valve is locked in its fully open position during the entire flight of the carrier, and is then closed very abruptly 120 after the carrier has discharged. Such an arrangement is highly advantageous since it ensures a full flow of air during the entire travel of the carrier and is not subject to the so-called "wire drawing" of the air 125 which takes place in many types of power apparatus, due to gradual, instead of abrupt, closure of the valve.

While I have illustrated a preferred embodiment of the invention, I wish it to be 130

understood that various changes in proportion of parts, relative position of the same, and the substitution of equivalents, may be made without departing from the spirit of 5 the invention.

I claim:

1. Power control apparatus for a pneumatic dispatch system of the minimum flow type having a transmission tube, means for 10 creating a carrier propelling air flow therethrough, and a controlling valve for governing such flow through the tube, a minimum flow being permitted when the valve is in closed position, said apparatus comprising 15 means for positively holding the valve in fully open position during the flight of a carrier through the tube.

2. Power control apparatus for a pneumatic dispatch system of the minimum flow type having a transmission tube, means for 20 creating a carrier propelling air flow therethrough, and a controlling valve for governing such flow through the tube, a minimum flow being permitted when the valve is in closed position, said apparatus comprising a spring actuated latch for holding the valve in fully open position during the 25 flight of the carrier through the tube.

3. Power control apparatus of the minimum flow type having a transmission tube, an exhauster, and a controlling valve for governing carrier impelling air flow through the tube, a minimum flow of air through the 30 tube being permitted when the controlling valve is in closed position, said apparatus comprising a pneumatic responding to pressure reduction in the tube due to introduction of a carrier therein and by such response opening the valve, means tending to close 35 the valve, and means independent of the pneumatic for holding the valve in open position so long as a carrier remains in the tube.

4. Power control apparatus of the minimum flow type having a transmission tube, an exhauster, and a controlling valve for governing carrier impelling air flow through the tube, a minimum flow of air through the 40 tube being permitted when the controlling valve is in closed position, said apparatus comprising a pneumatic responding to pressure reduction in the tube due to introduction of a carrier therein and by such response opening the valve, means for locking the 45 valve in open position, and means independent of the pneumatic for closing the valve.

5. Power control apparatus of the minimum flow type having a transmission tube, an exhauster, and a controlling valve for governing carrier impelling air flow through the tube, a minimum flow of air through the 50 tube being permitted when the controlling valve is in closed position, said apparatus comprising a pneumatic responding to pressure reduction in the tube due to introduction of a carrier therein and by such response opening the valve, a retaining latch for holding the valve in open position, and an air actuated vane moving in response to the delivery of a carrier from the tube and by its movement releasing the latch.

tion of a carrier therein and by such response opening the valve, releasable latch means for retaining the valve in open position, and means for closing the valve when the latch is released.

6. Power control apparatus of the minimum flow type having a transmission tube, an exhauster, and a controlling valve for governing carrier impelling air flow through the tube, a minimum flow of air through the 55 tube being permitted when the controlling valve is in closed position, said apparatus comprising a pneumatic responding to pressure reduction in the tube due to introduction of a carrier therein and by such response opening the valve, releasable locking means for holding the valve open, and means responsive to the delivery of a carrier from the tube to release the locking means thereby permitting the valve to close.

7. Power control apparatus of the minimum flow type having a transmission tube, an exhauster, and a controlling valve for governing carrier impelling air flow through the tube, a minimum flow of air through the 60 tube being permitted when the controlling valve is in closed position, said apparatus comprising a pneumatic responding to pressure reduction in the tube due to introduction of a carrier therein and by such response opening the valve, latch means for holding the valve open, and an air actuated element for releasing said latch.

8. Power control apparatus of the minimum flow type having a transmission tube, an exhauster, and a controlling valve for governing carrier impelling air flow through the tube, a minimum flow of air through the 65 tube being permitted when the controlling valve is in closed position, said apparatus comprising a pneumatic responding to pressure reduction in the tube due to introduction of a carrier therein and by such response opening the valve, retaining means for holding the valve in open position, and means responsive to the sudden rush of air through the tube incident to delivery of a carrier therefrom for releasing the valve to permit it to close.

9. Power control apparatus of the minimum flow type having a transmission tube, an exhauster, and a controlling valve for governing carrier impelling air flow through the tube, a minimum flow of air through the 70 tube being permitted when the controlling valve is in closed position, said apparatus comprising a pneumatic responding to pressure reduction in the tube due to introduction of a carrier therein and by such response opening the valve, a retaining latch for holding the valve in open position, and an air actuated vane moving in response to the delivery of a carrier from the tube and by its movement releasing the latch.

10. Power control apparatus of the mini-

- 40   13. Power control apparatus of the minimum flow type having a transmission tube, an exhauster, and a controlling valve for governing carrier impelling air flow through the tube, a minimum flow of air through the tube being permitted when the controlling valve is in closed position, said apparatus comprising a pneumatic responding to pressure reduction in the tube due to introduction of a carrier therein and by such response 110
- 45   opening the valve, a latch for retaining the valve in open position, a pivoted vane exposed to the air current flowing through the tube, stops limiting the arc of movement of the vane, yielding means normally holding the vane in inactive position, and a finger carried by the vane adapted to retract the latch and allow the valve to close when the vane swings to abnormal position. 115
- 50   14. Power control apparatus for a pneumatic dispatch system of the minimum flow type having a transmission tube and means for creating a carrier impelling air flow through the tube, said apparatus comprising a controlling valve for governing such flow, the controlling valve normally cutting off carrier impelling air flow, a minimum flow through the tube normally being permitted, a pneumatic which advances in response to decrease in pressure in the tube due to introduction of a carrier therein and thereby opens the valve, locking means independent of the pneumatic for positively holding the valve open during the flight of the carrier, and means for abruptly releasing the locking means when the carrier is delivered from the tube. 120
- 55   15. Power control apparatus for a pneumatic dispatch system of the minimum flow type having a transmission tube and means for creating a carrier impelling air flow through the tube, said apparatus comprising a controlling valve for governing such flow, the controlling valve normally cutting off carrier impelling air flow, a minimum flow through the tube normally being permitted, a pneumatic which advances in response to decrease in pressure in the tube due to introduction of a carrier therein and thereby opens the valve, means causing the pneumatic to retreat substantially to normal position during flight of the carrier, and positive means for holding the valve in fully open position during the flight of the carrier. 125
- 60   16. Power control apparatus for a pneumatic dispatch system of the minimum flow type having a transmission tube and means for creating a carrier impelling air flow through the tube, said apparatus comprising a controlling valve for governing such flow, the controlling valve normally cutting off carrier impelling air flow, a minimum flow through the tube normally being permitted, a pneumatic which advances in response to decrease in pressure in the tube due to introduction of a carrier therein and thereby opens the valve, means causing the pneumatic to retreat substantially to normal 130
- 65   tube being permitted when the controlling

- position during flight of the carrier, means independent of the pneumatic for closing the valve, and latch means retaining the valve in fully open position until the carrier is delivered from the tube. 65
- 5 17. Power control apparatus for a pneumatic dispatch system of the minimum flow type having a transmission tube and means for creating a carrier impelling air flow through the tube, said apparatus comprising a controlling valve for governing such flow, the controlling valve normally cutting off carrier impelling air flow, a minimum flow through the tube normally being permitted, 70
- 10 a pneumatic which advances in response to decrease in pressure in the tube due to introduction of a carrier therein and thereby opens the valve, a spring adapted to restore the pneumatic substantially to normal position during the flight of the carrier, a latch for holding the valve open during the flight of the carrier, a spring for closing the valve, and means for releasing the latch to permit the valve to close when the carrier is delivered from the tube. 75
- 15 18. Power control apparatus for a pneumatic dispatch system of the minimum flow type having a transmission tube and an ex-hauster, said apparatus comprising a controlling valve for governing carrier impelling air flow through the tube, a minimum flow of air being permitted when the controlling valve is in closed position, a pneumatic which moves in one direction in response to introduction of a carrier into the tube and thereby opens the controlling valve, the pneumatic being free to return to normal position independently of the valve, a spring tending to close the valve, and means for holding the valve open during the flight 80
- 20 of the carrier and for abruptly releasing the valve to allow it to close when the carrier is delivered from the tube. 85
- 25 19. Power control apparatus for a pneumatic dispatch system of the vacuum minimum flow type having a transmission tube, means for creating a carrier propelling air flow therethrough, a controlling valve for governing such flow through the tube, a minimum flow being permitted when the valve is in closed position, and means for opening the valve and positively holding it in fully open position during the flight of the carrier through the tube and for permitting the valve to close abruptly from its fully open position when the carrier is delivered from the tube. 90
- 30 20.
